UNITED STATES PATENT OFFICE.

JOSHUA STEVENS, OF CHICOPEE FALLS, MASSACHUSETTS.

CALIPERS AND DIVIDERS.

SPECIFICATION forming part of Letters Patent No. 337,531, dated March 9, 1886.

Application filed July 27, 1885. Serial No. 172,831. (No model.)

To all whom it may concern:

Be it known that I, JOSHUA STEVENS, a citizen of the United States, residing at Chicopee Falls, in the county of Hampden and State of Massachusetts have invented a certain new and useful Improvement in Dividers and Calipers, of which the following is a specification.

This invention relates to that class of dividers, calipers, or other analogous instruments wherein a spring is employed to separate the legs or arms; and it consists of a certain improvement in the construction by which the spring is connected to the legs, as will be hereinafter set forth.

15 In the accompanying drawings, Figure 1 is a side elevation of a pair of dividers constructed according to my invention. Fig. 2 is an edge view thereof. Fig. 3 is a side elevation of a pair of outside calipers. Fig. 4 is a side elevation of the legs near the joint and of the spring separated and drawn on a larger scale. Fig. 5 is a side elevation of the spring removed, and Fig. 6 is a cross-section cut on the line 6 6 in Fig. 1.

25 Referring to the drawings, let A A designate the legs or arms of the dividers or calipers, B the spring for separating them, and C the screw and D the nut for drawing them together. The screw and nut may be constructed 30 in any known way, as they form no part of the present invention. The legs A A may also be hinged or pivoted together at the head E in any known or suitable way.

The spring B is a C-spring, made of curved 35 plate, and arranged around and inclosing the head E, its ends coming down and joining the outer sides of the legs below the head. The ends of the spring are formed each with a rounded or cylindrical rib or bead, b b, turning outwardly. Each leg A is made with a 40 curved hook, a, curving upwardly and inwardly, and forming within it a cylindrical socket, c, adapted to receive the bead b on the spring. The spring is connected to the 45 legs by compressing it and sliding its beads b b endwise into the sockets c c. The ends of the spring tend to spring apart and so press outwardly against the hooks a a, whereby they

communicate their tension to the legs A A. The spring is held in place and prevented from being slipped out laterally by means of a screw, d, which is passed through one of the legs from the inside, as shown in dotted lines in Fig. 4 and in full lines in Fig. 6, and the end of which enters a notch, e, in the bead b on one end of the spring shown in Fig. 5.

I am aware that a C-spring has before been applied to dividers and calipers, its ends being provided with eyes, being bifurcated to embrace the legs, and having pins passed through their eyes and through holes in the legs. This construction necessitates making the spring considerably wider than the thickness of the legs at the points of their attachment, which is undesirable. My improvement avoids this necessity and dispenses with the pins, making a neater and simpler connection.

My invention is equally well adapted to inside calipers and to compasses and other analogous instruments.

What I claim as new, and desire to secure by Letters Patent, is—

1. The combination, with the legs of a pair of dividers, calipers, or other analogous instruments formed with outside hooks, a a, of a C-spring, the ends of which tend to press outwardly and are engaged by said hooks, substantially as set forth.

2. The combination, with legs A A, having hooks a a on their outer sides, forming sockets c c, of spring B, its ends formed with rounded ribs or beads b b, entering said sockets, substantially as set forth.

3. The combination of legs A A, having hooks a a on their outer sides, spring B, having its ends formed to engage said hooks, a a, notched at e, and a screw, d, entering said notch, substantially as set forth.

In witness whereof I have hereunto signed my name in the presence of two subscribers.

JOSHUA STEVENS
